UNITED STATES PATENT OFFICE.

ANDREW ANDERSON, OF GLENHAZEL, PENNSYLVANIA.

PROTECTED FLEXIBLE SHOE-SOLE.

1,134,803.

Specification of Letters Patent.

Patented Apr. 6, 1915.

Application filed November 28, 1914. Serial No. 874,448.

To all whom it may concern:

Be it known that I, ANDREW ANDERSON, a citizen of the United States, residing at Glenhazel, in the county of Elk and State of Pennsylvania, have invented certain new and useful Improvements in Protected Flexible Shoe-Soles, of which the following is a specification.

This invention relates to protected flexible shoe soles, and one of the principal objects of the invention is to provide a steel wire having points or prongs formed thereon for securing the wire in loops extending back and forth across the sole of the boot or shoe to form a protecting wear surface, and said wire being also provided with projecting studs which serve to prevent slipping.

Another object of the invention is to provide a protector for the sole of boots or shoes comprising a steel wire having prongs projecting from opposite sides thereof, said prongs being welded or connected to the wire in any suitable manner and said wire being bent in loops or in zig zag form to practically cover the sole of a boot or shoe in parallel strands properly spaced apart to serve as a protector and ice creeper.

These and other objects may be attained by means of the construction illustrated in the accompanying drawing, in which,

Figure 1 is a bottom plan view of a shoe sole having a protector secured thereto and made in accordance with this invention, Fig. 2 is a transverse sectional view taken on the line 2-2 of Fig. 1, Fig. 3 is a perspective view of a short length of the wire, Fig. 4 is a plan view of a short section of wire in which the prongs are triangular in form in cross section, Fig. 5 is a similar view showing the points or prongs of rectangular form in cross section, and Fig. 6 is a similar view showing the prongs of half round wire in cross section.

Referring to the drawing, the numeral 1 designates the sole of a boot or shoe, and 2 is the heel thereof. The sole protector comprises a steel wire 3 provided with a plurality of spaced prongs 4 extending from one side of said wire, said prongs adapted to be driven into the sole 1 of the boot or

shoe to hold the sole in place. The wire 3 is looped upon itself as shown by bending the ends in curved form as shown at 5 from opposite ends and leading the wire in a zig zag form from one end of the sole to the other, the loops at the middle being longer as at 6 than the end loops 5 and 7 and the strands 3 lying parallel one with the other and spaced apart about the same distance from the other.

The wire strands 3 are each provided with projecting studs or calks 8 which are spaced apart throughout the length of the wire, and these calks serve the desirable purpose of preventing slipping, and also assist in taking the wear of the sole. As shown in Fig. 3, the prongs 4 and the calks 8 are in the form of a pyramid, and in Fig. 4, the prongs and calks are triangular as shown at 9. As shown in Fig. 5 the calks and prongs are rectangular as shown at 10, while in Fig. 6, the prongs are half round, as shown at 11.

From the foregoing it will be obvious that a shoe sole protected as described will be flexible from end to end and that at the same time will be provided with a protecting wear element which can be readily driven into the sole to hold it in place and will also be provided with prongs or calks for preventing slipping.

Various changes may be made in the details of construction without departing from the spirit and scope of the invention as defined in the claim.

What is claimed is:—

A shoe sole provided with a wire protector formed of steel and having prongs projecting into the tread surface of the sole to hold the protector in place, said wire being extended back and forth across the sole, said wire having calks or prongs extending downwardly from the protector to prevent slipping.

In testimony whereof I affix my signature in presence of two witnesses.

ANDREW ANDERSON.
